ADJUSTABLE CURTAIN HOLDER

Herbert T. Funk, Pittsburgh, Pa.

Application March 12, 1936, Serial No. 68,396

1 Claim. (Cl. 248—274)

My invention relates to a holder, and while primarily intended for securing the ties of window curtains and drapes, it is obvious that the device may be employed for any other purposes 5 wherein it is found to be applicable.

Important objects of the invention are to provide a holder of the character described, which will facilitate the draping of window curtains and drapery, which is adjustable, simple in its construction and arrangement, durable and efficient 10 in its use, attractive in appearance, and comparatively inexpensive to manufacture.

With the foregoing and other objects in view which will appear as the description proceeds, 15 the invention consists of the novel construction, combination and arrangement of parts herein specifically described and illustrated in the accompanying drawing, but it is to be understood that changes in the form, proportions and details 20 of construction may be resorted to that come within the scope of the claim hereunto appended.

In the accompanying drawing, Figure 1 is a front view of a holder constructed in accordance with the invention, and Figure 2 is a side view 25 of a connecting hook embodied in the present invention.

Referring in detail to the drawing, 18 denotes a sheet metal, tubular, upright member. The member 1 is rectangularly-shaped in transverse 30 cross section, and comprises a back, a pair of forwardly disposed side walls, and a pair of in-turned front flanges 17. The latter have their free edges spaced from each other to provide a longitudinally extending slot 20 therebetween.

Each end of the back, of the member 18, is provided with an apertured lug for the reception of a fastening element, by which the said member is adapted to be secured in the vertical position against a window frame.

Each of the flanges 17, of the member 18, is provided with a plurality of spaced slots 19, which decline at angles to the horizontal and open into the vertical slot 20. The angularly disposed slots 19 are preferably horizontally aligned

in pairs, and are adapted for receiving and engaging the head 21 of a connecting hook 22. Any required number of connecting hooks 22 may be adjustably mounted in the member 18 to best meet conditions found in practice.

To prevent the removal and loss of the connecting hooks 22 from the member 18, the end portions of the side walls of the latter are turned inwardly toward each other to close the respective ends of said member.

In practice, a member 18 is fixed in the vertical position against the outer edge of each side member of a window frame, or on a window frame member which separates two adjacent windows. The hooks are adjusted to the angularly disposed 15 slots 19 at positions best suited to serve as connecting elements for attaching the ties thereto which are employed for securing the window curtains and draperies in their draped positions.

The present invention provides a simple and 20 most efficient device of its kind, which may be conveniently adjusted even by unskilled persons, and which will function effectively for the purposes intended in the manner herein set forth.

What I claim is:

A curtain holder comprising the combination of a sheet metal tubular upright member rectangularly-shaped in transverse cross section and including a pair of forwardly disposed side walls and a pair of in-turned front flanges, the free edges of said pair of front flanges being spaced from each other to provide a longitudinally disposed slot therebetween, each of said front flanges being provided with a plurality of spaced angularly disposed slots declining from the horizontal 30 and open into said longitudinally disposed slot, a connecting element including a head engaging in said member and being adjustable to extend same through and engage in any of said angularly disposed slots, the end portions of respective side 35 walls being turned inwardly toward each other to close the ends of said member for preventing the removal of said connecting element from the latter.
